(57) **CLAIM**

The ornamental design for a liquor dispenser, as shown and described.

DESCRIPTION

FIG. 1 is a top perspective view of a liquor dispenser, showing my design.

FIG. 2 is a bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a top perspective view thereof, shown in condition of use; and,

FIG. 10 is another top perspective view thereof, shown in condition of use.

The broken lines shown within the liquor dispenser depict portions of the dispenser which form no part of the claimed design. The broken lines showing glassware around the sides of the liquor dispenser depict environmental structure and form no part of the claimed design.

1 Claim, 10 Drawing Sheets
